185,817

CASE FOR PHOTOGRAPHIC EXPOSURE METER

Yukihiro Asano, Tokyo, Japan, assignor to U.S. Photo Supply Co. Inc., Washington, D.C., a corporation of Delaware

Application July 15, 1958, Serial No. 51,793

Term of patent 14 years

(Cl. D61—1)

Fig. 1 is a front elevational view of a case for a photographic exposure meter showing my new design.

Fig. 2 is a right side elevational view thereof.

Fig. 3 is a left side elevational view thereof.

Fig. 4 is a top plan view thereof.

Fig. 5 is a bottom plan view thereof.

Fig. 6 is a rear elevational view thereof.

Fig. 7 is a front elevational view thereof with the closure flap fully open.

The broken line showings of exposure meter, lanyard, and attaching clip in Figs. 1 to 7 are for illustrative purposes only.

I claim:

The ornamental design for a
